ABSTRACT OF THE DISCLOSURE

A centrifugal apparatus including a rotating support member for supporting sample containing vessels and a distributing chamber rotatable with the support member and adapted to receive liquid for distributing the same through cannulas to the vessels. The pressure in the distributing chamber is varied periodically to vary the level of the liquid in the vessels, and hence to agitate the said liquid in the vessels.

BACKGROUND OF THE INVENTION

This invention relates to centrifugal apparatus; and in particular, it relates to a means for agitating materials being treated in a centrifugal apparatus.

In the operation of a centrifugal apparatus it is necessary to keep the particles in the liquid in suspension so that they will be accessible to washing or other treatment with the liquid. This has been accomplished heretofore by mechanical stirring processes. For example, the cannulas carrying liquid from a central location into the vessels have been immersed periodically thereby causing stirring of the liquid therein. However, this process has several disadvantages. On the one hand, a rather complicated apparatus is necessary in order to carry out the periodic insertions and removal of the cannulas. Further, the mechanical action can have an undesirable effect on the particles suspended in the liquid. This is particularly true if the sample material is blood and the suspended particles are blood corpuscles.

Thus, there exists a need for a new and improved means for effecting agitation of the liquid in the vessels of a centrifugal apparatus, which means is more simplified than means known heretofore, and which means will not have an adverse effect on the particles suspended in the liquid.

SUMMARY OF THE INVENTION

A purpose of the present invention is to provide a new and improved arrangement for agitating the liquid in a centrifugal apparatus, which arrangement overcomes disadvantages in the devices known heretofore.

This purpose of the present invention is carried out by providing an arrangement wherein a gentle but nevertheless efficient agitation is obtained by varying the pressure, and hence also varying the level of the liquid in the sample containing vessels. More specifically, a means is provided for pulsating the pressure in the vessels thereby causing the liquid therein to oscillate, whereby agitation of the liquid in the vessels is obtained.

According to a preferred arrangement of the present invention, there is provided a support member mounted on a frame for rotation about an axis and including means for supporting one or more sample containing vessels. A distribution chamber is located on or about the axis of rotation and is also rotatable about the said axis. This chamber includes means for receiving a liquid to be subsequently delivered to the individual sample vessels, and also a separate aperture for each of the said vessels. A suitable conduit means extends from each of the said apertures into its respective sample vessel and to a point

2

therein below the normal level of the liquid contained therein. Thus, in operation as a centrifugal apparatus, the support member, the sample vessels and the distributing chamber are all rotated, in unison, as a result of which liquid flows from the distributing chamber through the conduit means to the respective sample vessels, and of course the centrifugal force is applied to the liquid in the vessels as the said members rotate about said axis.

In accordance with a main feature of the present invention, a means is provided for pulsating the pressure in the distributing chamber. Consequently, the pulsating pressure is felt by the liquid in the said vessels at the outer end of the conduit means. The vessels themselves are exposed at their upper ends to atmosphere so that the pressure variation in the conduit means causes the level of the liquid in the vessels and in the conduit means to oscillate, thereby agitating the said liquid.

In accordance with the present invention various means may be provided for causing the said pulsating pressure in the distributing chamber. For example, in one embodiment of the invention a pulsating device such as a vibrating diaphragm can be connected directly through a conduit, which would be concentric with the axis of rotation, into the distributing chamber. In another embodiment a continuous pressurized fluid pipe and a vent opening can be placed into fluid communication with the distributing chamber and in combination therewith an element rotatable with the distributing chamber to alternately obstruct first the pressure passage and then the vent passage to cause the said pulsating pressure in the distributing chamber.

Thus, it is an object of this invention to provide a new and improved arrangement for agitating the liquid in a centrifugal device.

It is another object of this invention to provide a new and improved centrifugal device including a means for agitating the liquid therein without mechanically contacting the liquid.

It is another object of this invention to provide an arrangement for agitating the liquid in a centrifugal apparatus by applying a pulsating pressure to the liquid in the vessels thereby causing the said liquid to oscillate.

It is still another object of this invention to provide a new and improved centrifugal apparatus having a support member for supporting and rotating sample vessels and including a rotating centrally mounted distributing chamber, and including means for pulsating the pressure within the distributing chamber and consequently pulsating the pressure of the liquid in the vessels to agitate the said liquid.

Other objects and the attendant advantages of the present invention will become apparent from the detailed description to follow together with the accompanying drawings.

BRIEF SUMMARY OF THE DRAWINGS

There follows a detailed description of preferred embodiments of the present invention, to be read together with the accompanying drawings. However, it is to be understood that the detailed description and accompanying drawings are provided only for purposes of illustration and that the invention is capable of numerous modifications and variations apparent to those skilled in the art.

FIG. 1 is a vertical cross-sectional view through the center of the apparatus and showing the center part and the elements on one side thereof, and omitting, for purposes of clarity, the identical part on the other side of the center part.

FIG. 2 is a vertical cross-sectional view taken through the center of a further embodiment of the invention and also showing, in addition to the central parts, certain

portions only on one side of the center line, omitting the corresponding parts on the opposite side for purposes of clarity.

FIG. 3 is a partial sectional view taken along a plane passing through line 3—3 of FIG. 2.

DETAILED DESCRIPTION OF THE PREFERRED EMBODIMENTS

Referring now to the drawings, FIG. 1 illustrates a first embodiment of the invention and FIGS. 2 and 3 illustrate a second embodiment of the invention. Elements in the second embodiment which correspond to elements in the first embodiment are indicated by the same numeral with a prime ('). Further, for purposes of clarity, the drawings show only those parts of the embodiments located on one side of the central axis of the centrifugal apparatus. It is to be understood, however, that both embodiments have rotational symmetry about this axis. Further, while only a single vessel is illustrated in FIG. 1, it is to be understood that any number of elements may be provided about the said central axis.

Referring now to FIG. 1, the apparatus includes a fixed housing part 1 having rotatably mounted therein a rotating support member 2 which is connected to the housing 1 through roller bearings 3. Rotational movement of the support member 2 is provided by a motor 6 which acts through a belt 5 to drive a belt pulley 4 which is fixed to the support member 2 for rotation therewith.

The support member 2 includes a plurality of recesses, only one of which is shown in the drawings, for receiving and supporting a sample vessel 7. This vessel includes an end opening 8 facing upwardly and radially inwardly.

A distributing chamber 10 and a central tubular member 12 are operatively connected to the support member 2 for rotation therewith. This connection is shown diagrammatically at 40 in FIG. 1. The distributing chamber 10 includes a plurality of apertures 11 spaced about the outer periphery thereof. Connected to each aperture 11 is a conduit means in the form of cannula 9 which places the interior of the distributing chamber 10 into fluid communication with the bottom of a sample vessel 7.

Liquid is supplied to the distributing chamber 10 by means of a pipe 13 which is non-rotatably fixed with respect to the fixed housing 1 and which extends through the central tubular member 12, and through a fluid seal 24, and through the upper opening 14 of the central tubular member 12 and into the distributing chamber 10. Upon rotation of the apparatus and owing to the centrifugal force, the liquid in the chamber 10 will then be urged against the outer annular surface 15 of the chamber 10 from which it will pass through the outlets 11 and the cannulas 9 into the sample vessels 7.

When centrifuging is performed and the liquid is supplied in this manner to the sample vessels, a surplus of liquid can drain off either through the opening 8 or, as indicated in the drawings, through an outlet 16 which is provided at a greater distance from the axis of rotation than the end opening 8. In this case, the liquid will collect in an annular space 17 formed in the supporting member 2; and to insure that the liquid passing through opening 16 is in fact directed to this space 17, the opening 16 is provided with a tubular section 18. The liquid collected in this manner in the space 17 can then flow off after the centrifuging has been completed through the aperture 19 formed in the supporting member 2 and subsequently through a drain tube 20 leading from the illustrated portion of the fixed housing 1.

To provide agitation of the liquid in the vessels at the desired times, so as to cause the particles in the vessels to rise from the bottoms thereof and be suspended, the chamber 10 is connected through a fluid seal O-ring 23, by means of a pipe 21 to a suitable pulsating device 22. By way of example, this device may comprise a motor operated vibrating diaphragm, one side of the diaphragm

enclosing a chamber in fluid communication with the pipe 21.

The apparatus of FIG. 1 would operate as follows. With support member 2 at rest, a number of sample vessels 7 are inserted onto the apparatus. Each of these vessels can be assumed to contain a small amount of liquid having solid particles therein. Such a liquid with solid particles can be blood, and the solid particles are then blood corpuscles to be washed, for example. The support member 2 is then rotated and liquid is supplied through the tube 13. The primary purpose of this liquid would be to dilute the liquid in the sample vessels 7. After a certain amount of cleaning liquid has been supplied, the pulsating device 22 can be operated for creating a pulsating pressure in the chamber 10. As a result of this, the liquid in the cannula 9 will oscillate about a median position which can be assumed to be represented by the dash line 25 in FIG. 1. The liquid in the cannula 9 will therefore be periodically be ejected from and withdrawn into the cannulas 9, thereby agitating the liquid in the cannulas 9 and of course also in the sample vessels 7.

The pulsating device 22 for creating the pulsating pressure in the container 10 might then be stopped, after which the particles suspended in the liquid would be centrifuged down towards the bottom or the radial outward end of the vessels 7. At this time additional liquid could be supplied through the tube 13 until liquid flows out of the openings 16 and 8. When the cleaning liquid has been exchanged in the sample vessels 7 in this manner, the pulsating device 22 may once again be started, after which the above described process is repeated any number of times. After the required washing has been completed, the supporting member 2 is stopped and the vessels 7 can be removed.

FIG. 2 illustrates another embodiment of the invention. This embodiment is similar to FIG. 1 in most respects, and hence many of the elements shown in FIG. 1 are omitted from FIG. 2. The main difference is that the embodiment of FIG. 2 illustrates another arrangement for causing the pulsating pressure in the distributing chamber.

In FIGS. 2 and 3 the central tubular member 12' is fixed with respect to the frame 1' and it is provided with a cover member 27, preventing liquid from flowing from the distributing chamber 10' down into the tubular member 12'. The upper portion of chamber 10' is closed by a sealing lid 26. A fluid inlet tube 13' passes through the tubular member 12' and the cover 27 for introducing liquid into the distributing chamber 10'. However, in this case, since the tubular member 12' does not rotate, it is not necessary that the pipe 13' be located on the axis of rotation of the distributor chamber 10'. A bearing surface 28 is provided between the engaging portions of the chamber 10' and the central tubular member 12'. A means for operatively connecting the chamber 10' with the member 2' for rotation therewith is shown diagrammatically at 41 in FIG. 2.

It will be noted that the upper portion of the tubular member 12' extends well into the distributor chamber 10'. On one side, this upwardly extending portion has an opening 30 in constant fluid communication with a conduit 29 through which compressed air would be continuously supplied. On the opposite side of the tubular member 12' there is provided an opening 31 for venting the distributing chamber 10'. The distributing chamber 10' includes an upwardly extending semicircular flange 32 which rotates therewith, continuously encircling the said upward portion of the tubular member 12'.

Thus, it can be seen that in operation, during one half-turn of the distributing chamber 10' (the half-turn illustrated in FIGS. 2 and 3) the chamber 10' is pressurized by means of its communication with conduit 29. After the chamber 10' has rotated one half-turn, the aperture 30 is closed by the flange 32, thereby breaking the

connection to pressure fluid pipe 29, and the aperture 31 is then opened to vent the chamber 10', thereby permitting a reduction in the pressure therein. This process is repeated periodically upon rotation of the chamber 10'.

Although the invention has been described in considerable detail with respect to preferred embodiments thereof, it will be apparent that the invention is capable of numerous modifications and variations apparent to those skilled in the art without departing from the spirit and scope of the invention. For example, in either embodiment the pulsating procedure need not take place continuously but can be set to take place only at specified times during the centrifuging process. Other modifications and variations are also apparent.

I claim:

1. A centrifugal apparatus comprising a frame, a support member mounted on the frame and rotatable about an axis, said support member including means for mounting at least one vessel thereon for rotation therewith about said axis, a distribution chamber also rotatable about said axis, conduit means normally placing said chamber in fluid communication with said vessel, and means for periodically varying the pressure in said chamber, thereby also varying the pressure in said vessel, whereby the level of any liquid present in the vessel is caused to vary, thereby causing agitation of such liquid.

2. The apparatus of claim 1 wherein said vessel includes a vent opening facing toward said axis, and said conduit means comprises a passage extending from said distribution chamber to a point in said vessel below a normal liquid level thereof, such that when liquid is present in the vessel to a level above said point and the pressure in the distribution chamber varies, the liquid level varies in the passage and hence also in the vessel, thereby agitating the said liquid.

3. The apparatus of claim 2 including a plurality of said vessels on said support member and spaced about said axis radially outwardly from said distribution chamber, said conduit means comprising a separate passage leading from said distribution chamber to each vessel.

4. The apparatus of claim 2 wherein said axis is substantially vertical and said support member rotates thereabout in a substantially horizontal plane, and wherein said passage is a cannula extending radially outwardly from said distribution chamber and passing downwardly through said vent opening to the lower part of said vessel.

5. The apparatus of claim 2 wherein the means for periodically varying the pressure in the distribution chamber varies the pressure in a regular cyclical manner.

6. The apparatus of claim 5 wherein the means for varying the pressure comprises a fluid pulsating device, and a pipe leading from said device into said distribution chamber.

5 7. The apparatus of claim 6 wherein said pipe is non-rotatably mounted on said frame, a fluid type seal, and wherein said pipe extends along said axis and through said seal into the chamber, whereby the chamber is rotatable relative to the pipe.

10 8. The apparatus of claim 7 including a central tubular member attached to and rotatable with said chamber about said axis, and a fluid inlet tube non-rotatably mounted on the frame and passing through said seal and through said tubular member along the said axis and entering the chamber across from the said pipe, said inlet tube being adapted to deliver liquid to the interior of said chamber, whereby the chamber is rotatable relative to the inlet tube.

15 9. The apparatus of claim 5 including a first passage 20 and a second passage leading to said chamber wherein said means for varying the pressure in the distribution chamber comprises a means for continuously supplying pressurized fluid to said first passage leading to said chamber, and wherein said second chamber leads from said chamber to vent, and means for alternately obstructing each of said first and second passages while leaving the other passage open to the chamber.

25 10. The apparatus of claim 9 including a tubular member non-rotatably mounted on said frame along the said axis, the said distribution chamber mounted on said tubular member for rotation thereabout, the said first and second passages leading from said tubular member to said chamber, and wherein said means for alternatively obstructing said passages comprises a flange rotatable 35 with the chamber and operable to alternatively cover said first and second passages.
